LOOM QUILL CAN

Filed June 23, 1936

UNITED STATES PATENT OFFICE

2,080,331

LOOM QUILL CAN

John C. Paddock, Spartanburg, S. C.

Application June 23, 1936, Serial No. 86,878

3 Claims. (Cl. 139—255)

This invention relates to filling carrier receptacles or quill cans for use with replenishing looms, to catch the exhausted carriers or quills as they are discharged or ejected from the shuttle by the transfer mechanism, all of which is well known in the loom art and is included in the filling replenishing mechanism that is disposed on either the right or left side of the loom.

The general object of the present invention is to provide a quill can constructed in a manner to catch and receive quills of all types and under all conditions, as such cannot be accomplished by the cans now in use, in that the quills strike a corner thereof and are generally thrown by impact away from the can and to the floor, resulting in damage to the quills or filling, thereby rendering the same unfit for further use.

Another object of the invention is to provide a quill can that can be supported in the same manner as cans and receptacles now in use and will fit the same space occupied thereby, consequently no change in the loom structure is required.

A further object of the invention is to provide a quill can that is simple in construction, inexpensive to manufacture and extremely efficient in use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a rear view of the can or receptacle which forms the subject matter of the present invention.

Figure 2 is a side view thereof with parts broken away and in section.

Figure 3 is a top plan view.

Figure 4 is a perspective view looking toward one corner thereof.

Referring to the drawing in detail, it will be noted that my can or receptacle includes all of the features of the can now in use, in that it is preferably formed from sheet metal and is relatively deep but is made in the two standard sizes which are classed as long and short, as well as for use on either side of the loom.

The front and side walls 1 and 2 respectively are preferably integral, and the front wall is of a greater height than the rear wall 3 which is preferably riveted or otherwise secured to the

side walls and bottom wall 4. The upper end of the front wall terminates in a rolled portion 5 to provide a handle and of course it is understood that the can is of the same width as the cans now in use, to be supported in the same manner below the filling replenishing mechanism.

The important feature of my can lies in the rear wall structure which includes an extension 6 for either side wall, that have their upper edges inclined toward the rear wall in the usual manner. The extension 6 is of substantially triangular configuration as shown, and is disposed in alignment with its side wall to extend outwardly therefrom for cooperation with the rear wall structure to enlarge the inlet of the can, as best shown in Figure 4. The upper portion of the rear wall, that is opposed to the extension 6 is outwardly flared as at 7 and thence is bent on a line 8 extending at a downward angle to provide a triangular portion 9 having its apex coinciding with the apex of the extension 6.

From that structure it will be seen that my can is provided with what may be termed an enlarged inlet, with the major portion of the enlargement disposed at one corner thereof, as in practice, it has been found that carriers or quills strike the inner corner portions of the straight rear type of can and are thrown to the floor, but with a can provided with the enlarged inlet directed outwardly at that corner, the quills are caught therein, thus preventing damage thereto or the filling thereof.

The upper edges of the side walls 2, the rear wall 3, and the extension 6 are crimped downwardly to reinforce the same, and the flanges provided by the downturned edges are notched at their point of connection with the bend lines of the rear wall and the extension.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A quill can for looms, comprising a receptacle including front, rear and side walls, a bottom and an open upper end, the latter providing the inlet for the receptacle, said front wall extending above the rear wall and the upper ends of the side walls being inclined downwardly from the front wall to the rear wall, a handle on the upper end of the front wall, said rear wall being

outwardly flared at its upper portion toward one corner of the receptacle, an extension formed on the outwardly flared portion and disposed at a rearward angle with respect thereto, said extension providing a portion of the side wall and cooperating with the outwardly flared portion to enlarge the inlet toward one corner thereof.

2. A quill can for looms, comprising a receptacle having an open upper end providing the inlet therefor, said receptacle including a rear wall and side walls, said rear wall at its upper portion being outwardly inclined from along and above an inclined line extending across said rear wall from a point substantially midway the upper and lower ends of the rear edge of one side wall, to the upper end of the rear edge of the

other side wall, and the first mentioned side wall being extended outwardly and connected to said portion for cooperation therewith to enlarge the inlet toward one corner thereof.

3. A quill can for looms, comprising a receptacle having an open upper end providing the inlet therefor, said receptacle including a rear wall and a side wall, said rear wall having its upper portion inclined outwardly toward one corner of the receptacle, from along and above an inclined line extending across said rear wall and an extension secured to the side wall and formed on said portion for cooperation therewith to enlarge the inlet toward one corner thereof.
